CLAIM

The ornamental design for a reaction tube, as shown and described.

DESCRIPTION

FIG. 1 is a front, top and right side perspective view of a reaction tube showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a cross sectional view take along line 8-8 in FIG. 2 thereof; and,

FIG. 9 is a cross sectional view take along line 9-9 in FIG. 2.

1 Claim, 8 Drawing Sheets(56)
